UNITED STATES PATENT OFFICE.

PAUL W. PRUTZMAN, OF BERKELEY, CALIFORNIA.

APPARATUS FOR DEHYDRATING OILS.

1,238,331.

Specification of Letters Patent. Patented Aug. 28, 1917.

Application filed May 6, 1913. Serial No. 765,804.

To all whom it may concern:

Be it known that I, PAUL W. PRUTZMAN, a citizen of the United States, and a resident of Berkeley, county of Alameda, and State 5 of California, have invented new and useful Improvements in Apparatus for Dehydrating Oils, of which the following is a specification.

Among the objects of this invention are 10 to quickly, simply and economically separate water or the lighter hydrocarbons from petroleum or the like, preparatory to its further refining or use as fuel; and

To provide simple and efficient means for 15 dehydrating a flowing stream of petroleum or the like.

The following description and the accompanying drawings will be devoted to the disclosure of the process and the means for dehydrating petroleum, but I do not wish to 20 be understood as limiting the scope of this invention to that particular substance.

This invention possesses other advantageous features which, with the foregoing, 25 will be set forth at length in the following description, where I shall outline in full that form of invention selected for illustration in the drawings accompanying and forming part of the present specification. The novelty 30 of the invention will be included in the claims succeeding said description. From this, it will be apparent that I do not restrict myself to the showing made by said drawings and description, as I may adopt many 35 variations within the scope of my invention as expressed in said claims.

In the drawings:

Figure 1 is a side elevation in cross-section 40 on the line I—I of a dehydrating apparatus constructed in accordance with this invention.

Fig. 2 is a plan view from above of the same, in cross section on the line II—II.

Fig. 3 is an end elevation of the same in 45 cross section on the line III—III.

Fig. 4 is an isometrical perspective of a section of the spray pipe from which the petroleum is discharged from the dehydrating coil.

50 In detail the construction consists of the closed retort 1, having the overflow pipe 2 therefrom: this overflow pipe discharges below the level of the liquid in the trap 3 which prevents the escape of vapors from 55 the retort through the overflow pipe. The same result can be attained by other arrange-

ment which will be obvious to those skilled in this art. From the trap the residual liquid is led away through the pipe 4 to a reservoir or into a further refining apparatus 60 not shown.

The vapors are drawn off from the retort through the exit pipe 5, which may be connected with a suitable condenser indicated 65 at 6.

The retort is preferably cylindrical and is provided with the heating coil 7 made up of pipe in any suitable arrangement to lie close to the shell 8 of the retort. The spacer pipes 9 are interposed between the shell of 70 the retort and the heating coil, to permit the contents of the still to circulate freely about the whole surface of the coil. The end 10 of the coil is led back to the steam generator (not shown) or exhausts into the air 75 as desired.

The petroleum is introduced into the still through the dehydrating conduit 11 surrounding the steam pipe until it branches out into the coil. The petroleum surrounding this steam pipe is preheated as it enters the still, so that the initial entrance of the cold oil will not cause a sudden drop of temperature in the still, particularly in the upper portion where a cold oil pipe would 85 cause a slight condensation of the vapors rising from the body of liquid in the still.

The dehydration tube 11 branches off at 12 and is formed into a coil 13 or other shape best adapted to absorb the heat radiated 90 from the heating coil 7. The dehydrating tube has a gradual descent from the inlet to the outlet.

Arranging the dehydration tube within 95 the retort effects a great economy in operation by conserving the heat, and also a saving of space, but other ways of heating the oil will suggest themselves to persons in this art.

A particular advantage in the use of this 100 invention resides in the spray discharge below the surface of a body of the liquid heated to the proper temperature. In the treatment of "foaming" oil, the foaming takes place in the dehydrating tube, from which 105 the vapors emerge through the restricted discharge openings in small quantities, not sufficient to seriously disturb the mass of oil in the retort.

The outlet length 14 of the tube 11 is 110 provided with one or more series of holes or jets 15 from which the petroleum issues

under pressure in fine streams or sprays. Practice has proven that jetting the heated oil thus materially aids, particularly in the "foaming" oils, the separation of the hydro-
5 carbons and lighter components from the residual mass, through which they rise as bubbles giving off any attached particles of oil to the mass through which they are passing, and from which they emerge as free
10 vapors to be drawn off by suction or otherwise through the exit 5.

The incoming stream of oil gradually assumes the temperature of the retort, which is the boiling point of water or the by-
15 products it is desired to separate by dehydration. The dehydrated residue passes off by overflow through the trap 3 as described.

The temperature of the retort is controlled by controlling the admission of steam
20 through the valve 16, and the admission of oil through the valve 17.

Water being a heavier mass will remain at the bottom of the retort until vaporized by the steam coil also located at that point,
25 in any event water cannot float out through the overflow pipe 2 and must eventually pass off with the vapors at 5 to be eliminated by suitable separators in the process of condensation. In separating the lighter hydro-
30 carbons the boiling point of which may be less than that of water, the water accumulating at the bottom of the retort can be drawn off through the tap 18 at the lowest point in the retort.

35 The particular advantages of this process and apparatus are the perfect control of the temperatures, the direct action and thoroughness of the dehydration, economy in

the use of heat, simplicity of the apparatus, its low initial cost, and compact self contained arrangement of the parts and the further fact that certain oils that "foam" and interfere with the usual processes of dehydration readily respond to treatment by this present process and apparatus.

Having thus described this invention, what is claimed and desired to be secured by Letters Patent is:

1. An apparatus for dehydrating oil comprising in combination a retort, a steam coil near the bottom of said retort but definitely spaced therefrom, a second coil through which oil is introduced into the retort, said second coil being placed immediately above the steam coil and having small apertures on its under surface whereby oil is projected in jets downwardly toward the steam coil, and means for preheating the oil before it is introduced into said second coil. 50

2. The process of treating hydrated oils which consists in driving off the lighter fractions of oil and water at a single operation by maintaining a body of petroleum in a closed still at approximately atmospheric pressure, and forcing small jets of heated hydrated oil against a heated body beneath the surface of said body of oil. 55

In testimony whereof, I have hereunto set my hand at San Francisco, California, this 70
16th day of April, 1913.

PAUL W. PRUTZMAN.

In presence of—

BALDWIN VALE,

HARRY L. BURLESON.
